Primary Examiner — Marianne Pandozzi(74) Attorney, Agent, or Firm — Davis Wright Tremaine LLP; George C. Rondeau, Jr.(57) CLAIM

The ornamental design for a beverage container, as shown and described.

DESCRIPTION

FIG. 1 is a top front perspective view of a beverage container showing my new design.

FIG. 2 is a front elevational view thereof.

FIG. 3 is a right side elevational view thereof.

FIG. 4 is a left side elevational view thereof.

FIG. 5 is a rear elevational view thereof.

FIG. 6 is a top plan view thereof.

FIG. 7 is a bottom plan view thereof.

FIG. 8 is a top front perspective view of a second embodiment thereof.

FIG. 9 is a front elevational view thereof.

FIG. 10 is a right side elevational view thereof.

FIG. 11 is a left side elevational view thereof.

FIG. 12 is a rear elevational view thereof.

FIG. 13 is a top plan view thereof.

FIG. 14 is a bottom plan view thereof.

FIG. 15 is a top front perspective view of a third embodiment thereof.

FIG. 16 is a front elevational view thereof.

FIG. 17 is a right side elevational view thereof.

FIG. 18 is a left side elevational view thereof.

FIG. 19 is a rear elevational view thereof.

FIG. 20 is a top plan view thereof; and,

FIG. 21 is a bottom plan view thereof

The broken lines represent portions of the beverage container that form no part of the claim.
